UNITED STATES PATENT OFFICE.

ANDREW C. KAPPES, OF CHICAGO, ILLINOIS, ASSIGNOR TO WILLIAM WRIGLEY JR. COMPANY, OF CHICAGO, ILLINOIS, A CORPORATION OF WEST VIRGINIA.

NUMBERING DEVICE FOR WRAPPING-MACHINES.

1,384,899.

Specification of Letters Patent. Patented July 19, 1921.

Application filed May 28, 1920. Serial No. 384,857.

To all whom it may concern:

Be it known that I, ANDREW C. KAPPES, a citizen of the United States, and a resident of Chicago, in the county of Cook and State 5 of Illinois, have invented certain new and useful Improvements in Numbering Devices for Wrapping-Machines, of which the following is a specification.

This invention relates to improvements in 10 wrapping machines, and more particularly to a numbering device adapted to be incorporated as a part of such machines, and adapted to accomplish a definite purpose or step; namely, that of impressing an identification character or numeral upon the individual packages which are wrapped by the machine.

The numbering device herein illustrated and described as embodying the features of 20 the invention, forms a part of a gum wrapping machine, used for wrapping the individual sticks in sheets of wax paper, and similarly wrapping a certain number of sticks together into package form, the package wrapper being preferably of wax, or 25 paraffined paper, preferably used by reason of its moisture-proof qualities.

The purpose of this invention is to provide 30 a numbering device whereby the individual packages may be identified by certain combinations of numerical characters or other characters of identification. In the manufacture of gum, it has been found that the quality of, or mixture of the ingredients 35 varies from time to time in spite of the care which is exercised in compounding the materials, with the result that occasionally a quantity of the finished product is placed on the market which does not come 40 up to the standard quality. In the event that the product is returned to the manufacturer, it is desirable that the packages bear some mark of identification in order that 45 the defect may be traced to its origin, and its cause rectified. Inasmuch as the mark of identification is of interest only to the manufacturer, it is desirable that such mark be inconspicuous so as not to be readily discernible by the purchasing public, but which 50 may be easily observed by the manufacturer, knowing just where the mark is to be found on the package.

For the reasons stated, a novel means of 55 applying marks of identification upon the

package wrappers of gum or like articles of consumption, has been devised, as will hereinafter be fully described and as illustrated in the accompanying drawings, in which—

Figure 1 is a view in elevation of a portion of a gum wrapping machine, showing the numbering machine and those parts of the wrapping machine associated therewith,

Fig. 2 is a view in vertical section taken 65 on line 2—2 of Fig. 1,

Fig. 3 is an enlarged detailed view of the numbering cylinder, and

Fig. 4 is a perspective view of a wrapped 70 package, showing the manner in which the identifying number is applied to the package wrapper.

The portion of the wrapping machine illustrated includes those parts with which the numbering device co-operates, and comprises in general those parts which advance the wrapping material which is fed from a roll in the form of a continuous strip, and those parts which cut the strip into short 75 lengths of predetermined size, these shorter lengths being the individual sheets which are wrapped about the articles to form the packages.

Considering first these parts of the wrapping machine, a vertical standard 1 is supported upon a horizontal frame member 2 of the machine, there being journaled in suitable bearings carried by said standard, a pair of horizontally arranged feed rolls 3—3, these rolls being mounted on rotative shafts 4—4 provided at their adjacent ends with intermeshing gear wheels 5—5, one of said shafts being driven by a prime mover of the machine through suitable driving elements. The wrapping material in the form of a continuous strip 6 is fed from a roll mounted, at some point above the standard 1 in a vertical direction downwardly between the feed rolls 3—3, there being preferably provided a guide roll 7 journaled at the upper end of the standard 1. Immediately below the feed rolls 3—3, and somewhat to the right, as shown in Fig. 2, is the cutting mechanism consisting of a reciprocating knife 8, preferably having a saw toothed arrangement of cutting edges, said reciprocating knife co-operating with a fixed knife blade 9 between which the strip 6 is fed. The strip is guided between the cut- 100

105

110

ting knives 8 and 9 by means of an inclined plate 10, and the sheets 11 after they are cut from the strip are guided downwardly between guide plates 12-12, and thence are 5 operated upon by those parts of the machine which wrap the sheets about the sticks of gum.

The numbering device, which will now be described in detail, is located adjacent to the 10 feed rolls 3-3 and the cutting mechanism so that the numbering operation is accomplished just before the strip is fed to the cutting mechanism. Locating the numbering device more definitely, the same is 15 mounted immediately above the feed rolls, and in such position that the impressions are made upon the strip 6 immediately before the latter passes between the feed rolls and into the cutting mechanism. In general 20 the numbering device consists of a numbering cylinder 13 extending horizontally and parallel with the plane of the strip 6, the periphery of the cylinder being substantially in contact with said strip 6 on one side 25 thereof. The numbering cylinder comprises a plurality of dials or numbering wheels 14 rotatively mounted upon a tubular shaft or sleeve 15, said shaft being journaled in suitable bearings 16-16 located at either 30 end of the cylinder, and secured to the standard 1. The numbering wheels 14 are of metal and have numerical characters 17 uniformly distributed around their peripheries, these numbers being arranged consecutively 35 from zero to nine about each wheel. The wheels are preferably of metal and the numerical characters being cast or otherwise formed so as to project from the surface of the wheels. Within the sleeve 15 is contained 40 a solid mass of suitable refractory material as at 18 (Fig. 3) in which is embedded a coil wire or resistance element 19 forming a part of an electric circuit, said resistance element terminating in conductors 45 19^a-19^a (Fig. 1) which are connected with a source of electrical energy. As shown in Fig. 1, the conductors 20-20 project from the end of the sleeve 15 which extends a considerable distance laterally beyond the side 50 of the vertical standard 1. It is apparent that if an electric current is passed through the resistance element 19 that heat will be generated, such heat being transmitted to the several wheels 14 of the numbering cylinder, 55 with the result that the temperature of the cylinder may be raised to the desired degree which, as will hereinafter be observed, is substantially that of the melting point of the wax, which cuts the strip 6. Manifestly, 60 electrical elements may be employed in conjunction with the heating coil for the purpose of regulating the temperature of the numbering cylinder, as well as of the numerical characters themselves.

65 It is now apparent that if the strip is

brought into contact with the numbering cylinder 13, and sufficient pressure is applied, that the temperature of the numeral characters 17 is sufficient to melt the wax with which the strip is impregnated, thus 70 forming an impression in the wax surface which is not unlike the "water mark" that is used extensively in identifying different grades of writing papers, and which is not readily discernible unless the paper is held 75 up to the light.

Inasmuch as it is desired to impress the numerical characters on each of the individual sheets 11 that are cut from the strip, it is proposed to provide means whereby the 80 strip 6 will be pressed against the heated numbering cylinder 13, at predetermined intervals or at predetermined points along the strip as the same is fed downwardly between the feed rolls 3-3. As a means for 85 accomplishing this end, there is mounted just below the feed rolls 3-3 a rock shaft 20, the same being the shaft which operates the oscillating cutting knife 8, the latter being connected to the lower ends of depending rocker arms 21-21 fixed to said rock shaft 20, as clearly shown in Fig. 1. The rock shaft 20 is journaled in suitable bearings, as 22-22, and is actuated by suitable operating mechanism including a crank arm 90 23 connected at one end of the rock shaft 20. Fixed to the rock shaft 20 at a point intermediate its ends and in vertical alignment with the numbering cylinder 13, is an arm 24 which extends vertically upward 100 and inwardly toward the numbering cylinder 13, terminating in an enlarged head or pad 25 having an inner face of some pliable material such as cork. The pad 25 normally occupies a position in horizontal 105 alignment with the axis of the numbering cylinder 13, and on the opposite side of the strip 6 from said cylinder, and substantially in contact therewith.

As a means for actuating the rocker arm 110 which in turn operates the oscillating cutter 8, as well as the pressure arm 24, the following mechanism is employed, as shown in Fig. 2:

A horizontal connecting rod 26 is pivotally connected to the end of the crank arm 23, and at its opposite end is provided with a yoke 27 which straddles a guide block 28 carried upon a rotative shaft 29 suitably supported and journaled in a vertical standard 30 integral with the frame 2 of the machine. Mounted upon the shaft 29 is a cam wheel 31 having formed therein an irregularly formed cam groove 32 which engages a cam projection 33 carried by the connecting rod 26. The cam groove is so designed as to transmit an intermittent reciprocating movement to the connecting rod 26, which in turn transmits an intermittent rocking movement to the rock shaft 20. Inasmuch 130

as the pressure arm 24 is actuated simultaneously with the cutting mechanism, it is obvious that it will produce an impression upon the advancing strip at predetermined intervals along the same, each impression being so located that when the strip reaches the cutting mechanism, an impression will be present upon each of the individual sheets 11 that form the individual package wrappers. Thus it will be seen that the operation of the numbering device is accurately timed with the cutting mechanism so that its operation is not dependent upon the rate at which the strip is fed through the machine, but rather upon the rapidity of the cutting operation. This being so, an impression on each individual package wrapper is assured.

The operation of the device is obvious so far as the manipulation of the numbering device is concerned. The numbering wheels 14 may be rotated by hand so that any desired combination of numerical characters can be obtained. Thus a single day's output may bear a certain number which may be changed from day to day. Thus the packages may be accurately identified in every respect. However, any system of identification may be adopted or other combination of identifying characters may be employed.

The invention is hereinafter more fully set forth in the appended claims.

I claim as my invention:

1. In a wrapping machine, the combination with means for advancing a continuous strip of paraffined wrapping material, and cutting mechanism for cutting said strip into sheets of predetermined lengths, of a numbering device comprising a heated impression member located adjacent the path of said strip, and a member operatively connected with said cutting mechanism to bring said strip into contact with said impression member, its operation being synchronized with said cutting mechanism to produce an impression in the paraffin on each sheet.

2. In a wrapping machine, the combination with means for advancing a continuous strip of wrapping material, cutting mechanism for cutting the same into separate wrapping sheets, of a numbering device comprising a series of heated numbering dials mounted upon a fixed axis parallel to and adjacent one side of said strip, a rocker arm having a strip engaging member positioned on the opposite side of said strip, and operatively connected with said cutting mechanism for pressing said strip against the numbering dials at predetermined intervals in the advancement of said strip.

3. In a wrapping machine, the combination with means for advancing a continuous strip of paraffin coated wrapping material, and mechanism for cutting the same in pre-

determined lengths, of a numbering device comprising an impression cylinder provided with raised characters located adjacent the path of said strip and in advance of said cutting means, an electrical heating unit associated with said cylinder, and a member carried by said cutting mechanism and operative to press said strip against said cylinder, its operation being synchronized with said cutting means to produce an impression in the paraffin coating on each length of said strip.

4. In a wrapping machine, the combination with means for advancing a continuous strip of paraffined wrapping material, mechanism for cutting the same into separate wrapping sheets and comprising a rock shaft, of a numbering device comprising an impression member mounted adjacent the surface of said strip and provided with heated characters, an arm having a pad at the end mounted on said rock shaft and operative in the cutting operation to press said strip against said impression member, thereby producing an impression in the paraffin.

5. A method of marking packages wrapped in paraffin material consisting of impressing a heated member bearing characters of identification against each individual sheet of wrapping material during the wrapping operation.

6. A method of marking packages adapted to be wrapped in sheets of material impregnated with a substance which melts at a predetermined temperature, and consisting of applying against each of said sheets a heated dial bearing raised characters, thereby impressing a mark of identification in the nature of a water-mark on each of said sheets.

7. A method of marking packaged goods wrapped in sheets of paraffined material, and consisting of successively applying at predetermined intervals along a continuous strip of material a dial bearing raised characters heated to a temperature sufficient to melt the paraffin in contact with the character prior to the cutting of the strip into separate sheets, and the wrapping of the goods in said sheets.

8. A method of marking packaged goods wrapped in sheets of paraffin coated material and consisting of pressing a continuous strip of such material against a dial bearing raised characters adapted to produce successively changing character combinations, said characters being heated to a temperature sufficient to melt the paraffin in contact with said characters, cutting the strip into sheets each bearing a series of characters, and wrapping each sheet about the goods to be packaged.

In witness whereof, I hereunto subscribe my name this 19th day of May, A. D. 1920.

ANDREW C. KAPPES.
